UNITED STATES PATENT OFFICE.

FRANK E. KINSMAN, OF PLAINFIELD, NEW JERSEY.

MEANS FOR RESETTING AUTOMATIC CONTROLLING DEVICES FOR VEHICLES OR TRAINS.

No. 868,993.

Specification of Letters Patent.

Patented Oct. 22, 1907.

Application filed January 29, 1906. Serial No. 298,321.

To all whom it may concern:

Be it known that I, FRANK E. KINSMAN, a citizen of the United States, and a resident of Plainfield, in the county of Union and State of New Jersey, have invented certain new and useful Improvements in Means for Resetting Automatic Controlling Devices of Vehicles or Trains, of which the following is a specification.

This invention relates to means for resetting automatic controlling devices of vehicles or trains, and particularly to automatic controlling devices of that class adapted for controlling and stopping the movement of such vehicle or train.

One of the principal objects of the invention is to reduce accidents to the minimum by rendering it very difficult for a careless engineer or motorman to restart his train or vehicle after it has been brought automatically under control or stopped, and I accomplish this by requiring that the resetting of the automatic controlling means shall be effected by more than one person or from more than one point.

In one embodiment of my invention illustrated herein in the controlling points from which the resetting of the automatic controlling or train-stopping mechanism is effected are separated by such a distance that in practice the separate or joint action of two or more persons will be required to increase the speed of or start a train or car that has been automatically brought under control or stopped. Thus the responsibility for the advance of a train or car into a danger zone will be divided, and will rest upon two or more persons, one of whom may be the engineer or motorman, and another or others, employees having other duties than such engineer or motorman. By dividing the responsibility in this manner it becomes unnecessary to employ two persons having identical duties for the purpose of reducing the danger of accidents, and it would, for example, be unnecessary to employ two engineers in the cab in order to avoid the risk that one man, if alone in the cab, might take chances and run past a signal set against him. As set forth in my prior patents and applications, it is frequently unnecessary for a car or train to be brought to a full stop by the action of the automatic means for controlling the movement thereof, it being sufficient in many cases, and particularly in cities and on interurban roads where trains are run at short intervals, to bring the train or car under control and then proceed past the danger point at reduced speed. In such cases, however, it is desirable, in the use of my automatic train-stopping system, to provide some check upon an engineer or motorman who may be desirous of proceeding too rapidly or at full speed immediately after the automatic controlling action has taken place. By providing means for preventing the resetting of the automatic controlling means except from two or more points distant

from one another, or by the concurrence of action of two or more minds, although the responsibility for proceeding is divided, a careless or reckless engineer or motorman will be less of a menace to passengers and equipment than one who is allowed to run his train or car without any exercise of supervisory or joint authority.

The two or more points of control referred to in the preceding paragraph need not necessarily be governed by two or more persons. Indeed, on trains, especially long trains, it is very desirable to provide for the resetting of a plurality of automatic controlling devices from a single point by a single person, as for example, for the resetting of all the automatic controlling devices on a long train by the engineer, motorman or other person, from a single point when it would not be feasible to employ a large number of persons for resetting the controlling devices on all the cars of the train separately, as for example, on a long-distance or transcontinental train. In such cases it is more important that the engineer shall have full control over all the cars of a train, where trains are far apart on a line, than on railroads in cities or connecting adjacent towns where the running of a large number of trains at short intervals is the chief consideration. Thus it will be seen that the resetting of a controlling device from any one of a plurality of points, and the resetting of a plurality of controlling devices from a single point are necessary to, and have their special advantages in, the running of cars or trains under the conditions specified, and various combinations and modifications of these features of control may be adapted for use under various conditions, and will be herein-after described and claimed.

In the drawings accompanying this specification and forming part of the present application, Figure 1 is a side elevation of a train of cars embodying automatic controlling means of such construction as to comprise the feature of control of a single train-controlling device from a plurality of points or by a plurality of persons, on a single car, and also the feature of control of different train-controlling devices on different cars of a train from points or by persons on different cars of such train; Fig. 2 is an enlarged view of one of the cars shown in Fig. 1 and illustrates more in detail than in Fig. 1 how the automatic controlling means and associated devices are so constructed and combined as to constitute a unit which may be independent of every other similar unit of a train; Fig. 3 is a view similar to Fig. 2 of a portion of a car illustrating a modification of my invention in which the resetting of the automatic controlling device is governed electrically instead of by fluid pressure, as in Figs. 1 and 2. Fig. 4 is an enlarged detail illustrating in sectional end elevation an improved automatic controlling device of the type adapted for automatically releasing the pressure in an

air-brake system of a power-operated vehicle or train, and shows the parts in their normal idle position; Fig. 5 is a sectional side elevation of the same, with the parts in the same position; Fig. 6 is a view similar to Fig. 5, but illustrates the parts in the positions they assume when the device is in the working position; Fig. 7 is an enlarged transverse section of the valve of said device, which valve is a detail which will be hereinafter described; Fig. 8 is a sectional end elevation, 10 similar to Fig. 4, of the modified type of controlling device which is electrically operated, and which is illustrated in Fig. 3; Fig. 9 is a view similar to Fig. 2, showing a modification of my invention in which the automatic train-controlling device is governed electrically from a plurality of points instead of by fluid pressure, as in Figs. 1 and 2; and Fig. 10 is a view similar to Fig. 1 illustrating another modification of my invention, in which the separate controlling units of each car of a train are connected in such a manner as 20 to constitute a controlling system all of the automatic controlling devices of which are resettable from a single point or by a single person.

Similar characters designate like parts in all the figures of the drawings.

25 Referring first to Figs. 1 and 2, I have illustrated in these views one of the most common ways in which an automatic controlling device for governing the power, brakes or other movement-controlling medium of a vehicle or train may be reset from any one of a plurality 30 of points. In the first of these views two cars are shown coupled together, and in the second view one of the cars comprising the train illustrated in Fig. 1 is shown on a larger scale. In each case each car, which may be of any usual or suitable type of construction, has thereon 35 means for automatically applying a brake or brakes, the particular means illustrated being an automatic fluid-pressure brake system, such as the usual air-brake system. Only so much of the air-brake system is illustrated as is necessary for proper coöperation with the 40 automatic controlling means hereinafter to be described. Here each car has the usual train-pipe 2 of an automatic air-brake system, and that section of the train-pipe which is carried by a car is connectible by the usual flexible couplings or hose-pipes 3 at opposite ends 45 of the car with corresponding sections of the train-pipe on other cars through similar flexible connections. The sections of the train-pipe and the different flexible connections for coupling them together are designated in Fig. 1 by the same reference characters. These 50 couplings 3 embody the usual valves (not shown) for preventing escape of air when the couplings are separated.

55 Preferably each car and its controlling and resetting devices illustrated in Figs. 1 and 2, constitutes a car-unit capable of operation independently, but connectible to other car-units and also capable of coöperation therewith as an element or unit of a train. This coöperation is intended to be effected by means of the usual coupling devices for the cars and for the train- 60 pipe sections carried by such cars, only the connections for the sections of the train-pipe being shown herein.

65 Any suitable type of automatic controlling device for operating upon the power, brakes, etc., may be employed, but this device will usually be an automatic

brake-controlling device coöperative with the brake system. The particular construction of this automatic controlling device may be varied within wide limits, but I prefer to make use of a type of brake-controlling device similar to that shown, described and claimed in 70 an application filed by me August 16, 1905, Serial No. 274,370. The present device differs from that shown in said application, however, in that no means other than the pressure of fluid in the air-brake system is used for resetting the brake-controlling device. In 75 Figs. 4, 5, 6 and 7 I have illustrated in detail the construction of the brake-controlling device shown in a general way in Figs. 1 and 2. The chief element of such an automatic brake-controlling device is usually an arm normally extending into the path of operation 80 of a trip (not shown) located on the road-bed of the line of way, and in the construction illustrated herein I have shown such an arm, but it differs in many respects from those heretofore used. As is usual, it controls the movement of an automatic valve the stem of which 85 is shown at 4 and the body of which is contained within a valve-casing 5. This valve-casing is connected by means of a pipe 6, also substantially as is usual, with the train-pipe 2, and through the open end of said pipe which is extended beyond the valve-casing and communicates with the open air, pressure in the brake system may be let off in the usual manner when the valve in the casing 5 is so turned as to open the pipe 6. Normally, however, this pipe is closed by said valve when the controlling arm is in the position shown in Figs. 1, 90 2, 4 and 5, and the pipe 6 is closed to communication with the outer air. The principal means for controlling the opening of the valve in the casing 5 and releasing the pressure in the brake-pipe system and thereby applying the brake or brakes of a car or train, is an automatic controlling arm or trip 7 secured to the valve-stem 4, a nut 8 and a pin 9 being shown on the end of said valve-stem for locating the controlling arm in its proper plane of movement. This controlling arm or trip depends into the path of a trip-arm on the line of 95 way, and when said trip-arm, which may be of the usual type and operated in the ordinary manner, is elevated and the controlling arm 7 comes in contact with the trip-arm, said controlling arm is shifted to one side of its vertical position, as for example, to the position 100 shown in Fig. 6, and carries with it the valve-stem 4 and the valve connected thereto, the movement of the parts being such as to open communication between the pipe 6 and the outer air. The principal difference between the controlling arm 7 here shown and that ordinarily used is that in this construction said arm has a cross-head 10 having at opposite sides of the long axis of the controlling arm stop faces 11 in line with the axis of oscillation of the arm. The object of this cross-head and its faces is to assure proper coöperation between 110 the controlling arm and resetting means therefor, which will now be described.

115 It is customary to reset a controlling-arm manually, but in the present case, as in some of my prior patents and application, I prefer to employ means for automatically resetting the controlling-arm. This automatic resetting means may be of any suitable type, provided that it is capable of operating upon the automatic train-controlling means in the manner set forth in the preamble hereof. That illustrated in connection with 120 125

Figs. 1 to 7 inclusive is intended particularly to coöperate with the automatic controlling means in such a manner as to be capable of resetting such controlling means, that is, a single controlling device, from any one 5 of a plurality of points, and hence by any one of several persons. In addition to this the resetting means shown in said views conforms to the characteristics of a fluid-pressure brake-system in that, as shown, the resetting function is controlled by fluid pressure, although of course it is not essential that the resetting be effected by such means. When the resetting is effected by fluid pressure the fluid pressure may be derived from any suitable source, as for example, from the main reservoir (not shown) of the brake-pipe system, through an 10 independent pipe 12 leading to a manual controller or handle 13, which normally shuts off communication between the pipe 12 and the pipe 14 leading to a cylinder and piston for resetting the controlling arm 7. The pipe 14 in the car-unit shown in Figs. 1 and 2 preferably 15 extends from end to end of the car and has manual controlling handles 13 at both ends of the car, the manual controlling handles, pipes and valves being duplicated in the construction shown at opposite ends of the car, and the parts being designated by the same 20 reference characters. The pipe 14 I term a resetting pipe, and this resetting pipe on each car in said figures, is independent of the resetting pipe of every other car. At a suitable point therein a branch pipe 15 leads from 25 said resetting pipe into one end of a cylinder adjacent to the controlling arm 7. This cylinder, which is designated generally by 17, consists of two main parts and an intermediate partition, the main portion or barrel of the cylinder being shown at 18 as cast integral with the bracket-arm 19 extending from the valve-casing 5, 30 while the partition, which is indicated at 20, rests on the upper end of said barrel and is secured to the barrel of the cylinder by a separate casing or cover 21 constituting the head of the cylinder, this casing or head being fastened to the barrel of the cylinder in this case 35 by screws 22 which extend through the head and the partition and into the barrel 18. At its upper end the branch pipe 15 is screwed into the casing or head 21. The partition 20 has a central tapered opening 23 normally closed by the correspondingly tapered head 24 40 of a valve 25 loosely seated therein. The shank portion 25 of this valve has long longitudinal grooves 26 cut therein, as by means of a milling-cutter, for the purpose of permitting pressure from the pipe 15 to be applied through the opening 23 when the valve is raised 45 as illustrated in Fig. 6. The valve will only be raised when the controlling arm 7 is in the position shown in said view, that is, when an automatic application of the brakes has been effected and the parts are in such positions as to require resetting to the normal positions. 50 For the purpose of resetting or returning the controlling arm 7 to its normal central position I prefer to make use, in the construction just described, of a resetting piston mounted and working in the barrel 18 of the cylinder 17, this piston being, when the parts are 55 in the positions shown in Fig. 6, in communication with the source of pressure connected with the resetting pipe 15, through the opening 23 in the partition 20 and the channels 26 in the valve 25. When pressure is admitted through the pipe 15 into the space behind the piston, which is designated by 27, said piston will be 60 forced outward or downward and will operate upon suitable means for resetting the controlling arm in the central position. This application of pressure to the piston will only take place when some one of the manual resetting handles 13 is turned to open communication 65 between the pipes 12 and 14. The means for transmitting the movements of the piston 27 to the cross-head 10 and contact-faces 11 of the controlling arm 7 may be of any suitable type. A simple means for effecting this movement is a yoke 28 connected to a 70 short piston-rod 29 to which the piston 27 is secured. This yoke reciprocates with the piston and constitutes a trip-resetting device, and is so constructed that the faces 30 thereof coöperate respectively with the working faces or contact faces 11 of the cross-head of the controlling arm 7, and serve as stops for limiting the respective movements of said controlling arm at opposite sides of its central position, and has actuating faces for turning said controlling arm by engagement with one or the other of the contact faces 11 of the cross-head. 75 The manner in which the yoke and the piston are forced up and with them the valve 25 on an automatic application of the brakes, and the manner in which these parts are returned to the normal central position when pressure is applied to the piston through the resetting pipe 15, will, it is believed, be clear from Figs. 80 5 and 6, the piston and the trip-resetting device or yoke always moving in a right line to turn the trip back to its normal position. At 31 I have shown a vent which is uncovered by the piston when the piston reaches the 85 limit of its downward movement, this vent serving, in a manner which will be well understood by reference to my prior patents, as a means for permitting the escape of the operating fluid remaining in the cylinder space, etc. 90

In Figs. 3 and 8 I have illustrated a modification of my invention which shows a controlling apparatus and resetting means of the same type as that illustrated in Figs. 1 and 2, that is to say, one in which the resetting means on each car of a train is independent of that on 95 every other car and constitutes a unit. One of the principal differences, however, between the construction shown in these views and that illustrated in Figs. 1 to 7 inclusive is that there is illustrated only a single point of control on each car for governing the resetting 100 operation on such car. The chief specific difference, however, between the devices shown in these two sets of views is that in Figs. 3 and 8 the resetting is controlled and effected electrically instead of from a fluid-pressure system. The car, the automatic controlling 105 arm, its valve, and the train-pipe and other coöperative devices, are the same as those shown in the preceding views, and are designated by the same reference characters. The means for controlling the resetting, however, is altogether different. As shown, it comprises a 110 manual resetting handle in the form of a switch-lever 13' carried by a suitable switch-box and stand 32 and 33. A conductor 12' corresponding to the pipe 12 from the source of fluid pressure in the previous views, leads 115 from a source of energy or battery 34 corresponding to the reservoir (not shown) from which the pipe 12 leads, and conductors 14' and 35 lead respectively from the switch-box and the other side of the battery 34 to the coils of an electromagnet adjacent to the controlling 120 arm or trip 7. The casing 18', the end-piece or part- 125

ton, which is designated by 27, said piston will be 130

tion 20' and the cover or head 21', are analogous to the corresponding parts in the previous views. The coils 27' of the magnet are contained in the casing 18' and are wound around a central tube 36 in the well-known manner, opposite terminals of this magnet being connected with the conductors 14' and 35 respectively. This magnet is in the form of a solenoid the core of which is shown as a two-part one, one member being the shank 29' of a yoke 28' similar to the yoke previously described, while the other is a detachable core-piece 29".

When the controlling-arm or trip 7 in Fig. 8 is shifted to the position shown in Fig. 6 it forces up the yoke and the core attached thereto, and these parts remain in such position until the switch-arm 13' is moved onto the contact 37, whereupon the coils of the solenoid being energized, the core 29'—29" will be drawn downward and will carry with it the yoke, which will reset the controlling arm or trip 7 in the same manner that it is reset by the piston in Fig. 6.

In Fig. 9 I have illustrated another modification of the invention, in which the resetting is effected by electrical means, as in Figs. 3 and 8, but the resetting is preferably from a plurality of points on the car, as is the case with the apparatus controlled by fluid pressure shown in Figs. 1 and 2. Indeed, the only difference between Figs. 3 and 9 is that two controlling handles or switch-levers 13' are shown instead of one, as in Fig. 3, and two switch-boxes and posts 32 and 33. One of these resetting handles or switch-levers, with its switch-box and post, is preferably placed at each end of the car. The source of energy controlled by the switch-levers 13' and the conductors leading therefrom are substantially similar to the corresponding connections in Fig. 3, and the parts which correspond thereto are designated by the same reference characters. The conductor leading from the negative pole of the battery to the right-hand switch-lever 13' is, however, designated by 35', and the conductor leading from said right-hand switch-box to the automatic controlling device is designated by 14". The principal feature which distinguishes this electrical resetting apparatus having two different points of control from the corresponding fluid-pressure actuated resetting apparatus shown in Figs. 1 and 2 is that in Fig. 9 the concurrence of two operations is required to effect the closing of the circuit which operates to reset the controlling arm or trip 7, whereas in the system shown in Figs. 1 and 2 only a single controlling operation is necessary to accomplish this result. This is due to the fact that either of the resetting handles 13 in Figs. 3 and 2 is capable of admitting pressure to the piston of the resetting means by opening communication with the main reservoir, regardless of whether the other resetting handle is operated, whereas in Fig. 9 neither resetting handle 13' is by itself capable of closing the circuit through the battery, it being necessary to operate both of the switch-levers 13' and close both breaks in the circuit before current will flow, the joint action of a plurality of devices thus being necessary in the construction shown in Fig. 9 for governing the resetting.

In Fig. 10 I have illustrated the application of the second main feature of the present invention to the resetting of automatic controlling devices which have been automatically actuated. This second main fea-

ture relates to the resetting of a plurality of automatic devices from a single point of control, and is especially adapted and intended for use on long trains, as for example, express trains running infrequently between cities at a great distance from each other, and on trans-continental trains, on trains of which type it is desirable that every automatic controlling device, whether for brakes, power, or otherwise, on every car of the train, shall be at all times under the control of a single individual, to wit, the engineer or motorman in the cab of the locomotive or in the first car of the train. In this view I have also deemed it preferable to illustrate as the automatic controlling means an automatic fluid-pressure-actuated resetting system for an automatic fluid-pressure or air-brake system, and all of the parts shown in said view are similar to corresponding parts shown in Fig. 1 and are designated by the same reference characters as the parts in Fig. 1. The essential difference between the two views is that while the resetting means on each car of the train illustrated in Fig. 85 1 constitutes a unit and is unconnectible with any other unit of the train, the resetting means on each car of the train shown in Fig. 10, while also constituting a unit capable of independent operation when the car is uncoupled from another car or cars of a train, is capable also of dependent operation as an element of a train by being connectible with other like or similar units of another car or cars of a train. When such connectible like or similar resetting units as are illustrated in Fig. 10 are actually connected, communication between the sections of the resetting pipe 14 on all such cars is effected, and each of such sections is continuously in communication with every other. This connection may be effected advantageously in the same manner as the connection of the sections of the train-pipe of the fluid-pressure brake system of the train, that is to say, by means of flexible coupling pipes or hose-pipes 38 similar to those shown at 3 for coupling the sections of the train-pipe. Each of the coupling pipes 38 should also be provided at its coupling end with a valve for the purpose of preventing change in or loss of pressure in the resetting pipe when the sections of said pipe are uncoupled. The valved connections for joining such flexible coupling pipes for the train-pipes of the brake system being well understood in the art, and the corresponding connections used by me for coupling the resetting pipes being preferably identical in construction, are not illustrated herein in detail. The result of connecting the sections 14 of the resetting pipe in the manner just described, so as to form a continuous resetting train-pipe capable of being connected independently with a source of fluid pressure from a main reservoir on any car of the train, will be evident. By turning any manual resetting handle 13 at any point on the train and from any point on any car, all of the resetting pistons on every car of the train may be almost instantaneously put in communication with and operated from a source of fluid pressure on any car of a train or from the cab of the locomotive. Thus, the resetting of all automatic controlling arms on every car of the train may be simultaneously effected from a single point on the train, and this point may be controlled either by the engineer or motorman at the front of the train, or, if desired, by any conductor, guard, or other authorized person at any other point on the train.

I have not shown in the drawings hereof the brakes by means of which the rotation of the car-wheels is checked or stopped, for the reason that these brakes are of well-known construction; and any suitable or well-known 5 brake mechanism may be employed in connection with the fluid-pressure system and the resetting means, the particular construction of the brakes and brake mechanism being dependent upon the nature of the fluid-pressure system used for controlling the 10 brakes.

What I claim is:

1. The combination with a power-operated vehicle, of an automatic controlling device thereon governed by a danger condition on a line of way and movable from one 15 position to another for controlling the movement of the vehicle, and means for resetting said controlling device from any one of a plurality of points.

2. The combination with a power-operated vehicle, of an automatic controlling device thereon governed by a danger 20 condition on a line of way and movable from one position to another for controlling the movement of the vehicle, and means for resetting said controlling device from any one of a plurality of points on the vehicle.

3. The combination with a power-operated vehicle, of an 25 automatic controlling device thereon governed by a danger condition on a line of way and movable from one position to another for controlling the movement of the vehicle, and means for resetting said controlling device from a plurality of points.

30 4. The combination with a power-operated vehicle, of an automatic controlling device thereon governed by a danger condition on a line of way and movable from one position to another for controlling the movement of the vehicle, and means for resetting said controlling device from a plurality of points on the vehicle.

5. The combination with a power-operated vehicle, of an automatic controlling device thereon governed by a danger condition on a line of way and movable from one position to another for controlling the movement of the vehicle, and 40 a plurality of devices each of which governs the resetting of said controlling device.

6. The combination with a power-operated vehicle, of an automatic controlling device thereon governed by a danger condition on a line of way and movable from one position 45 to another for controlling the movement of the vehicle, and a plurality of devices on the vehicle each of which governs the resetting of said controlling device.

7. The combination with a power-operated vehicle, of an automatic controlling device thereon governed by a danger 50 condition on a line of way and movable from one position to another for controlling the movement of the vehicle, and a plurality of devices conjointly governing the resetting of said controlling device.

8. The combination with a power-operated vehicle, of an 55 automatic controlling device thereon governed by a danger condition on a line of way and movable from one position to another for controlling the movement of the vehicle, and a plurality of devices on the vehicle conjointly governing the resetting of said controlling device.

60 9. The combination with a power-operated vehicle, of an automatic controlling device thereon governed by a danger condition on a line of way and movable from one position to another for controlling the movement of the vehicle, and a plurality of devices at opposite ends of said vehicle 65 each of which governs the resetting of said controlling device.

10. The combination with a power-operated vehicle, of an automatic controlling device thereon governed by a danger condition on a line of way and movable from one 70 position to another for controlling the movement of the vehicle, and a plurality of devices at opposite ends of said vehicle conjointly governing the resetting of said controlling device.

11. The combination with a power-operated vehicle, of an 75 automatic brake-controlling device thereon governed by a danger condition on a line of way and movable from one position to another for controlling the application of a

brake, and means for resetting said brake-controlling device from any one of a plurality of points.

12. The combination with a power-operated vehicle, of an 80 automatic brake-controlling device thereon governed by a danger condition on a line of way and movable from one position to another for controlling the application of a brake, and means for resetting said brake-controlling device from any one of a plurality of points on the vehicle.

13. The combination with a power-operated vehicle, of an 85 automatic brake-controlling device thereon governed by a danger condition on a line of way and movable from one position to another for controlling the application of a brake, and a plurality of devices each of which governs the resetting of said brake-controlling device.

14. The combination with a power-operated vehicle, of an 90 automatic brake-controlling device thereon governed by a danger condition on a line of way and movable from one position to another for controlling the application of a brake, and a plurality of devices conjointly governing the resetting of said brake-controlling device.

15. The combination with a power-operated vehicle, of an 95 automatic brake-controlling device thereon governed by a danger condition on a line of way and movable from one position to another for controlling the application of a brake, and manual controllers at opposite ends of the vehicle each of which governs the resetting of said controlling device.

16. The combination with a power-operated vehicle, of an 100 automatic brake-controlling device thereon governed by a danger condition on a line of way and movable from one position to another for controlling the application of a brake, and manual controllers at opposite ends of the vehicle conjointly governing the resetting of said controlling device.

17. The combination with a power-operated vehicle and with a fluid-pressure brake system thereon, of an automatic 105 brake-controlling device on the vehicle and governed by a danger condition on a line of way and movable from one position to another for controlling the application of a brake, and means for resetting said brake-controlling device from any one of a plurality of points.

18. The combination with a power-operated vehicle and with a fluid-pressure brake system thereon, of an automatic 110 brake-controlling device on the vehicle and governed by a danger condition on a line of way and movable from one position to another for controlling the application of a brake, and means for resetting said brake-controlling device from any one of a plurality of points on the vehicle.

19. The combination with a power-operated vehicle and with a fluid-pressure brake system thereon, of an automatic 115 brake-controlling device on the vehicle and governed by a danger condition on a line of way and movable from one position to another for controlling the application of a brake, and a plurality of devices each of which governs the resetting of said brake-controlling device.

20. The combination with a power-operated vehicle and with a fluid-pressure brake system thereon, of an automatic 120 brake-controlling device on the vehicle and governed by a danger condition on a line of way and movable from one position to another for controlling the application of a brake, and a plurality of devices conjointly governing the resetting of said brake-controlling device.

21. The combination with a power-operated vehicle and with an air-brake system thereon, of an automatic brake-controlling device on the vehicle and governed by a danger 125 condition on a line of way and movable from one position to another for controlling the application of an air-brake, and means for resetting said brake-controlling device from any one of a plurality of points.

22. The combination with a power-operated vehicle, of an automatic controlling device thereon governed by a danger condition on a line of way and movable from one position to another for controlling the movement of the vehicle, and fluid-operated means for resetting said controlling device from any one of a plurality of points.

23. The combination with a power-operated vehicle and with a fluid-pressure brake system thereon, of an automatic 130 brake-controlling device on the vehicle and governed by a danger condition on a line of way and movable from one position to another for controlling the application of a

- matic brake-controlling device thereon movable from one position to another for controlling the application of a brake, a similar fluid-pressure system for resetting said brake-controlling device, and a plurality of valves at different points in said second system for controlling the pressure therein. 5
46. The combination with a power-operated vehicle and with an air-brake system thereon, of an automatic brake-controlling device thereon movable from one position to another for controlling the application of a brake, a similar air-pressure system for resetting said brake-controlling device, and means for controlling the pressure in said second system from any one of a plurality of points. 10
47. The combination with a power-operated vehicle and with a fluid-pressure brake system thereon, of a valve in said system, an automatic trip controlling said valve and movable from one position to another, and manually-controlled means on the vehicle for positively resetting said trip. 15
- 20 48. The combination with a power-operated vehicle and with a fluid-pressure brake system thereon, of a valve in said system, an automatic trip controlling said valve and movable from one position to another, and means for resetting said trip from any one of a plurality of points. 25
49. The combination with a power-operated vehicle and with a fluid-pressure brake system thereon, of a valve in said system, an automatic trip controlling said valve and movable from one position to another, and means for resetting said trip from any one of a plurality of points on the vehicle. 30
50. The combination with a power-operated vehicle and with a fluid-pressure brake system thereon, of a valve in said system, an automatic trip controlling said valve and movable from one position to another, and a plurality of devices conjointly governing the resetting of said trip. 35
51. The combination with a power-operated vehicle and with an air-brake system thereon, of a valve in said system, an automatic trip controlling said valve and movable from one position to another, and means for resetting said trip from any one of a plurality of points. 40
52. The combination with a power-operated vehicle and with a fluid-pressure brake system thereon, of a valve in said system, an automatic trip controlling said valve and movable from one position to another, and fluid-operated means for resetting said trip from any one of a plurality of points. 45
53. The combination with a power-operated vehicle and with a fluid-pressure brake system thereon, of a valve in said system, an automatic trip controlling said valve and movable from one position to another, fluid-operated means for resetting said trip, and a plurality of fluid-controlling devices each of which governs said fluid-operated means. 50
54. The combination with a power-operated vehicle and with a fluid-pressure brake system thereon, of a valve in said system, an automatic trip controlling said valve and movable from one position to another, fluid-operated means for resetting said trip, and a plurality of fluid-controlling devices conjointly governing said fluid-operated means. 55
55. The combination with a power-operated vehicle and with a fluid-pressure brake system thereon, of a valve in said system, an automatic trip secured to said valve and movable from one position to another, and means including a cylinder and a resetting piston for positively resetting said trip. 60
- 65 56. The combination with a power-operated vehicle and with a fluid-pressure brake system thereon, of a valve in said system, an automatic trip controlling said valve and movable from one position to another, and means including a cylinder and a resetting piston for resetting said trip from any one of a plurality of points. 70
57. The combination with a power-operated vehicle and with a fluid-pressure brake system thereon, of a valve in said system, an automatic trip controlling said valve and movable from one position to another, and means including a cylinder and a resetting piston for resetting said trip from any one of a plurality of points on the vehicle. 75
58. The combination with a power-operated vehicle and with a fluid-pressure brake system thereon, of a valve in said system, an automatic trip controlling said valve and movable from one position to another, means including a cylinder and a resetting piston for resetting said trip. 80
- cylinder and a resetting piston for resetting said trip, and a plurality of devices each of which governs the operation of said resetting piston. 85
59. The combination with a power-operated vehicle and with a fluid-pressure brake system thereon, of a valve in said system, an automatic trip controlling said valve and movable from one position to another, means including a cylinder and a resetting piston for resetting said trip, and a plurality of devices conjointly governing the operation of said resetting piston. 90
60. The combination with a power-operated vehicle and with a fluid-pressure brake system thereon, of a valve in said system, an automatic trip secured to said valve and movable from one position to another, and a fluid-pressure system including a cylinder and a resetting piston for positively resetting said trip. 95
61. The combination with a power-operated vehicle and with a fluid-pressure brake system thereon, of a valve in said system, an automatic trip controlling said valve and movable from one position to another, a fluid-pressure system including a cylinder and a resetting piston for resetting said trip, and a plurality of valves each of which governs the operation of said resetting piston. 100
62. The combination with a power-operated vehicle, of an automatic trip controlling the movement of said vehicle and movable from one position to another, and manually controlled means for positively resetting said trip. 105
63. The combination with a power-operated vehicle, of an automatic trip controlling the movement of said vehicle and movable from one position to another, and manually controlled means on the vehicle for positively resetting said trip. 110
64. The combination with a power-operated vehicle, of an automatic trip controlling the movement of said vehicle and movable from one position to another, a trip-resetting device for positively resetting said trip, and manually-controlled means for actuating said trip-resetting device. 115
65. The combination with a power-operated vehicle, of an automatic trip controlling the movement of said vehicle and movable from one position to another, a trip-resetting device for positively resetting said trip, and manually-controlled power-operated means for actuating said trip-resetting device. 120
66. The combination with a power-operated vehicle, of an automatic trip controlling the movement of said vehicle and movable from one position to another, a trip-resetting device for positively resetting said trip, and a cylinder containing a power-operated piston for actuating said trip-resetting device. 125
67. The combination with a power-operated vehicle, of an automatic trip controlling the movement of said vehicle and mounted to swing about an axis from one position to another, and manually-controlled means for positively resetting said trip. 130
68. The combination with a power-operated vehicle, of an automatic trip controlling the movement of said vehicle and mounted to swing about an axis from one position to another, a trip-resetting device for positively resetting said trip, and manually-controlled means for actuating said trip-resetting device. 135
69. The combination with a power-operated vehicle, of an automatic trip controlling the movement of said vehicle and mounted to swing about an axis from one position to another and having a cross-head, a yoke for actuating said cross-head, and manually controlled means for actuating said yoke. 140
70. The combination with a power-operated vehicle, of an automatic trip controlling the movement of said vehicle and mounted to swing about an axis from one position to another and having a cross-head, a cylinder containing a power-operated piston, and a yoke secured to said piston for actuating said cross-head. 150
71. The combination with a power-operated vehicle, of an automatic trip controlling the movement of said vehicle and mounted to swing about an axis from one position to another and having a cross-head the working face of which intersects said axis, a yoke for engaging the working face of said cross-head and turning said trip, and means for actuating said yoke. 155
72. The combination with a power-operated vehicle, of 160

an automatic trip controlling the movement of said vehicle and mounted to swing about an axis from one position to another, and a trip-resetting device movable in a right line for positively resetting said trip.

5 73. A power-operated railway car having thereon the following coöperative elements, viz.—an automatic controlling device movable from one position to another for controlling the movement of the car, and means for resetting said controlling device—said coöperative elements 10 constituting a car-unit unconnectible with any other car-unit.

74. A power-operated railway car having thereon the following coöperative elements, viz.—an automatic controlling device movable from one position to another for controlling the movement of the car, and a plurality of devices 15 each of which governs the resetting of said controlling device—said coöperative elements constituting a car-unit unconnectible with any other car-unit.

75. A power-operated railway car having thereon the following coöperative elements, viz.—an automatic controlling device movable from one position to another for controlling the movement of the car, and a plurality of devices 20 each of which governs the resetting of said controlling device—said coöperative elements constituting a car-unit unconnectible with any other car-unit.

76. A power-operated railway car having thereon the following coöperative elements, viz.—an automatic brake-controlling device movable from one position to another for controlling the application of a brake, and means for 30 resetting said brake-controlling device—said coöperative elements constituting a car-unit unconnectible with any other car-unit.

77. A power-operated railway car having thereon the following coöperative elements, viz.—an automatic brake-controlling device movable from one position to another for controlling the application of a brake, and fluid-operated means for resetting said brake-controlling device—said coöperative elements constituting a car-unit unconnectible with any other car-unit.

40 78. A power-operated railway car having thereon the following coöperative elements, viz.—an automatic brake-controlling device movable from one position to another for controlling the application of a brake, means including a source of fluid power for resetting said brake-controlling 45 device, and means for controlling said fluid power—said coöperative elements constituting a car-unit unconnectible with any other car-unit.

79. A power-operated railway car having thereon the following coöperative elements, viz.—an automatic brake-controlling device movable from one position to another for controlling the application of a brake, means including a source of air-pressure for resetting said brake-controlling device, and means for controlling said air-pressure—said coöperative elements constituting a car-unit unconnectible with any other car-unit.

50 80. A power-operated railway car having thereon the following coöperative elements, viz.—an automatic brake-controlling device movable from one position to another for controlling the application of a brake, a fluid system 60 for resetting said brake-controlling device, and a plurality of devices located at different points each of which governs the resetting of said brake-controlling device by the fluid in such system—said coöperative elements constituting a car-unit unconnectible with any other car-unit.

65 81. A power-operated railway car having thereon the following coöperative elements, viz.—an automatic trip for controlling the movement of said vehicle and movable from one position to another, and means for resetting said trip—said coöperative elements constituting a car-unit unconnectible 70 with any other car-unit.

82. A power-operated railway car having thereon the following coöperative elements, viz.—an automatic trip for controlling the movement of said car and movable from one position to another, and means including a cylinder 75 and a resetting piston for resetting said trip—said coöperative elements constituting a car-unit unconnectible with any other car-unit.

83. A power-operated railway car having thereon the following coöperative elements, viz.—an automatic trip 80 for controlling the movement of said car and movable

from one position to another, and a fluid-pressure system including a cylinder and a resetting piston for resetting said trip—said coöperative elements constituting a car-unit unconnectible with any other car-unit.

84. A train of power-operated vehicles, each of which 85 vehicles has thereon the following coöperative elements, viz.—an automatic controlling device movable from one position to another for controlling the movement of the vehicle, and means for resetting said controlling device—the coöperative elements on each vehicle being independent 90 of the others.

85. A train of power-operated vehicles, each of which vehicles has thereon the following coöperative elements, viz.—an automatic controlling device movable from one position to another for controlling the movement of the vehicle, and manually-controlled means for resetting said controlling device—the coöperative elements on each vehicle 95 being independent of the others.

86. A train of power-operated vehicles, each of which vehicles has thereon the following coöperative elements, 100 viz.—an automatic controlling device movable from one position to another for controlling the movement of the vehicle, and means for resetting said controlling device from any one of a plurality of points—the coöperative elements on each vehicle being independent of the others.

87. A train of power-operated vehicles, each of which vehicles has thereon the following coöperative elements, viz.—an automatic controlling device movable from one position to another for controlling the movement of the vehicle, and a plurality of devices each of which governs 110 the resetting of said controlling device—the coöperative elements on each vehicle being independent of the others.

88. A train of power-operated vehicles, each of which vehicles has thereon the following coöperative elements, viz.—an automatic controlling device movable from one position to another for controlling the movement of the vehicle, and a plurality of devices conjointly governing the 115 resetting of said controlling device—the coöperative elements on each vehicle being independent of the others.

89. A train of power-operated vehicles, each of which vehicles has thereon the following coöperative elements, 120 viz.—an automatic brake-controlling device movable from one position to another for controlling the application of a brake, and means for resetting said brake-controlling device—the coöperative elements on each vehicle being independent of the others.

90. A train embodying a fluid-pressure brake system and made up of power-operated vehicles, each of which vehicles has thereon the following coöperative elements, viz.—an automatic brake-controlling device movable from one 125 position to another for controlling the application of a brake, and means for resetting said brake-controlling device—said coöperative elements on each vehicle being independent of the others.

91. A train embodying an air-brake system and made up of power-operated vehicles, each of which vehicles has thereon the following coöperative elements, viz.—an automatic brake-controlling device movable from one position to another for controlling the application of an air-brake, and means for resetting said brake-controlling device—said coöperative elements on each vehicle being independent of the others.

92. A train embodying a fluid-pressure brake system and made up of power-operated vehicles, each of which vehicles has thereon the following coöperative elements, viz.—an automatic brake-controlling device movable from one position to another for controlling the application of a brake, and fluid-operated means for resetting said brake-controlling device—said coöperative elements on each vehicle being independent of the others.

93. A train embodying a fluid-pressure brake system and made up of power-operated vehicles, each of which vehicles has thereon the following coöperative elements, viz.—an automatic brake-controlling device movable from one position to another for controlling the application of a 135 brake, and fluid-controlling devices each of which governs the resetting of said brake-controlling device—said coöperative elements on each vehicle being independent of the others.

94. A train embodying a fluid-pressure brake system and 140

- made up of power-operated vehicles, each of which vehicles has thereon the following coöperative elements, viz.—a automatic brake-controlling device movable from one position to another for controlling the application of a 5 brake, means including a source of fluid-power for resetting said brake-controlling device, and means for controlling said fluid-power—said coöperative elements on each vehicle being independent of the others.
95. A train embodying a fluid-pressure brake system and 10 made up of power-operated vehicles, each of which vehicles has thereon the following coöperative elements, viz.—an automatic brake-controlling device movable from one position to another for controlling the application of a brake, means including a source of air-pressure for resetting 15 said brake-controlling device, and means for controlling said air-pressure—said coöperative elements on each vehicle being independent of the others.
96. A train embodying a fluid-pressure brake system and 20 made up of power-operated vehicles, each of which vehicles has thereon the following coöperative elements, viz.—an automatic brake-controlling device movable from one position to another for controlling the application of a brake, fluid system for resetting said brake-controlling device, and a plurality of devices located at different points 25 each of which governs the resetting of said brake-controlling device by the fluid in such system—said coöperative elements on each vehicle being independent of the others.
97. A train of power-operated vehicles, each of which vehicles has thereon the following coöperative elements, 30 viz.—an automatic trip for controlling the movement of said vehicle and movable from one position to another, and means for resetting said trip—the coöperative elements on each vehicle being independent of the others.
98. A train embodying a fluid-pressure brake system and 35 made up of power-operated vehicles, each of which vehicles has thereon the following coöperative elements, viz.—a valve in said brake system, an automatic trip controlling said valve and movable from one position to another, and means for resetting said trip—said coöperative elements 40 on each vehicle being independent of the others.
99. A train embodying a fluid-pressure brake system and 45 made up of power-operated vehicles, each of which vehicles has thereon the following coöperative elements, viz.—a valve in said brake system, an automatic trip controlling said valve and movable from one position to another, and means including a cylinder and a resetting piston for resetting said trip—said coöperative elements on each vehicle being independent of the others.
100. A train embodying a fluid-pressure brake system and 50 made up of power-operated vehicles, each of which vehicles has thereon the following coöperative elements, viz.—a valve in said brake system, an automatic trip controlling said valve and movable from one position to another, and a fluid-pressure system including a cylinder and a resetting piston for resetting said trip—said coöperative elements on each vehicle being independent of the others.
101. A train of power-operated vehicles, each of which vehicles has thereon an automatic controlling device governed by a danger condition on a line of way and movable from one position to another for controlling the movement of said vehicle, and means for resetting all of said controlling devices from a single point on the train.
102. A train of power-operated vehicles, each of which vehicles has thereon an automatic brake-controlling device governed by a danger condition on a line of way and movable from one position to another for controlling the movements of such vehicle, and means for resetting all of said 60 brake-controlling devices from a single point on the train.
103. A train of power-operated vehicles, each of which vehicles has thereon an automatic controlling device governed by a danger condition on a line of way and movable from one position to another for controlling the movement of said vehicle, and means for resetting all of said controlling devices from any one of a plurality of points on the train.
104. A train of power-operated vehicles, each of which vehicles has thereon an automatic brake-controlling device governed by a danger condition on a line of way and movable from one position to another for controlling the movement of such vehicle, and means for resetting all of said 70 brake-controlling devices from any one of a plurality of points on the train.
105. A train of power-operated vehicles, each of which vehicles has thereon an automatic controlling device governed by a danger condition on a line of way and movable from one position to another for controlling the movement of such vehicle, and means for resetting all of said controlling devices from any one of a plurality of points on different vehicles of the train.

Signed at New York, in the county of New York, and State of New York, this 20th day of January A. D. 1906.

FRANK E. KINSMAN.
